U. S. PATENT OFFICE.

No. 23.

1861.

WHOLE No. 1,388.

Cook Stoves.

N. S. VEDDER, OF TROY, N. Y.

Letters Patent for a Design, No. 23, dated March 5, 1861.

SPECIFICATION.

TO ALL WHOM IT MAY CONCERN:

Be it known, that I, N. S. VEDDER, of Troy, in the county of Rensselaer and the State of New York, have invented or produced a certain new and useful design for Cook Stove plates; and I do hereby declare that the following is a full, clear, and exact description of the same, reference being had to the annexed drawings, with the letters of reference marked thereon, forming part of this specification, in which—

Fig. 1 is a plan view of the plates, and

Fig. 2 and 3, sectional views, showing the curvatures of the plates.

The description of my design for cook stove plates is as follows, viz: A is a cook stove side or jamb plate, with a swelled panel or bag a at the top, and a raised panel D at the bottom. C is an ornament placed at one end; b and b' are curved sunk panels at each end of the plate. E and B are the oven doors, having respectively for ornaments on their panels a sheaf of wheat F and the scales G. H and I are mouldings of the oven doors.

Having fully described my design, what I claim as new and desire to secure by Letters Patent, is—

The ornamental design and configuration of cook stove plates, such as herein described and shown in the annexed drawings.

N. S. VEDDER.
